TUBE AND BOTTLE CLOSURE

Ward B. Jenks, Youngstown, Ohio, assignor to
Mildred N. Jenks, Youngstown, Ohio

Application December 24, 1937, Serial No. 181,563

3 Claims. (Cl. 221—60)

This invention relates to a tube or bottle closure.

The principal object of this invention is the provision of closure means adapted to be threaded upon the neck of a bottle or collapsible tube so as to provide a more convenient form of closure.

A still further object of this invention is the provision of a tube or bottle closure means adapted to be threaded upon the neck of a tube or bottle and provided with a tapered orifice which forms a restricted opening in the tube or bottle.

A further object of the invention is the provision of a tube or bottle closure adapted to be formed upon a tube or bottle by the formation of one portion of the device in the structure of the said tube or bottle.

A still further object of the invention is the provision of a closure means for a tube or bottle and having a snap-like means of holding the cap in position.

The tube or bottle closure means shown and described herein has been designed to be applied to the threaded neck portion of a collapsible tube or a small bottle so as to provide a convenient closure means. The closure means consists primarily of a threaded collar and a cap adapted to snap thereon, the cap and the bottle being additionally connected by means of a ball and socket.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

The invention is illustrated in the accompanying drawing, wherein:—

Figure 1 is a side elevation of a bottle showing the closure means threaded upon the neck thereof.

Figure 2 is a side elevation of a collapsible tube showing the closure means threaded upon the neck thereof.

Figure 3 is a greatly enlarged detail view, in cross section, of the closure means as adapted for use upon a bottle and showing a modification in the form of a restricted orifice as a portion of the device.

Figure 4 is an enlarged detail view of the closing means, with parts in cross section, showing a portion of the closing means formed as a part of a collapsible tube.

By referring to the drawing, and Figures 1 and 2 in particular, it will be seen that a closure means comprising a cap 1 having a convenient lever 2 formed as a part thereof is attached to a threaded collar 3 by means of a ball and socket joint 4 and has as a means of holding the cap 1 securely upon the collar 3 a snap-like structure 5. This assembled closure means may be threaded upon any bottle neck or collapsible tube, the diameter of the threaded portion of the collar 3 determining the particular adaption. This closure means has been designed primarily as an accessory closure means to be applied to a bottle or collapsible tube in place of the usual threaded cap.

By referring to Figure 3 of the drawing, it will be seen that a greatly enlarged detail view, in cross section, of the closure means is shown as applied to a bottle, a modification being included in that a restricted orifice 6 has been formed in the threaded collar portion 7 of the device. This modified closure means including a restricted orifice is designed to be applied to a bottle containing liquid so that the liquid may be dispensed a few drops at a time. This modification is particularly adapted to bottles containing various hand lotions and similar articles.

By again referring to Figure 3 it will be seen that a cap portion 8 is provided with a convenient lever 9 and a snap locking means comprising an annular shoulder 10 formed upon the threaded collar 7 and a matching annular groove 11 formed within the cap portion 8. It is understood that the cap 8 and collar 7 are formed of moulded rubber or other material sufficiently resilient to enable the snap-like arrangement to function. A ball 12 formed upon the cap 8 and positioned in a socket 13 in the threaded collar 7 serves as a pivot and holds the cap 8 securely upon the collar 7.

By referring to Figure 4 of the drawing, it will be seen that a modification is provided in that the threaded collar portion of the device has been formed as a collar 14 of a collapsible tube, an annular shoulder 15 being provided thereon and adapted to receive a cap 16 having an annular groove 17 therein. The groove 17 and shoulder 15 are formed so as to provide a snap-like section when engaged. A ball 18 is formed upon the cap 16 and functions within a socket 19 formed in the collar 14 of the collapsible tube.

It is obvious that the closure means shown and described herein may be varied according to size, both as to the threaded collar portion and to the restricted orifice if and when formed therein.

It is apparent that the successful operation of the closure means depends upon the formation of the device of a suitable slightly resilient material so that the snap-like provision will be operative and the ball pivot means insertable into the socket means provided.

5 What I claim is:—

- 10 1. A closure means adapted for use upon a bottle or tube and comprising a collar having a socket formed therein, a cap having a ball formed thereon adapted to function with the said socket in such manner that the cap is pivoted on the said ball and socket in opening and closing, an annular shoulder formed on said collar and an annular groove formed within said cap adapted to function together in a snap-like manner, a lever formed on the said cap adapted to provide a convenient thumb rest for operating the said closure means.
- 15 2. A closure means adapted for use upon a bottle or tube and comprising a collar having a restricted orifice formed therein, a socket formed

in said collar and a cap having a ball formed thereon adapted to function with the said socket in such manner that the cap is pivoted on the said ball and socket, an annular shoulder formed on said collar and an annular groove formed within said cap adapted to function together in a snap-like manner, a lever formed on said cap adapted to provide a convenient thumb rest for operating the said closure means.

5 10 3. A tube or bottle closure comprising a tube or bottle having a collar formed thereon and provided with a socket therein, a cap provided with a ball adapted to function within the said socket so that the said cap may be pivoted upon the said ball and socket, an annular shoulder formed upon the said collar and an annular groove formed within the said cap, the said shoulder and groove adapted to function together in a snap-like manner, a lever formed on the said cap adapted to provide a convenient thumb rest for operating the said closure.
